UNITED STATES PATENT OFFICE

124,052

DESIGN FOR A JET NOZZLE

Raymond W. Wilson, Glendale, Calif.

Application August 3, 1940, Serial No. 94,193

Term of patent 14 years

To all whom it may concern:

Be it known that I, Raymond W. Wilson, a citizen of the United States, residing at Glendale, in the county of Los Angeles and State of California, have invented a new, original, and ornamental Design for a Jet Nozzle, of which the following is a specification, reference being had to the accompanying drawing, forming part thereof.

Fig. 1 is a perspective view of a jet nozzle showing my new design,

Fig. 2 is a front elevational view,

Fig. 3 is a side elevational view, and,

Fig. 4 is a rear elevational view thereof.

I claim:

The ornamental design for a jet nozzle, as shown.

RAYMOND W. WILSON.
